UNITED STATES PATENT OFFICE.

FRED S. SHAFFER, OF SINES, MARYLAND.

STREET-SWEEPING MACHINE.

1,151,408.

Specification of Letters Patent. Patented Aug. 24, 1915.

Application filed January 27, 1914. Serial No. 814,751.

To all whom it may concern:

Be it known that I, FRED S. SHAFFER, a citizen of the United States, residing at Sines, in the county of Garrett and State of Maryland, have invented new and useful Improvements in Street-Sweeping Machines, of which the following is a specification.

This invention relates to improvements in street sweeping machines and has particular application to a machine of the class described whereby the dirt and refuse may be swept up and carted away.

In carrying out the present invention, it is my purpose to provide a street sweeping machine which will embody among other features an endless traveling brush inclined relatively to the horizontal and having a portion of the lower run thereof disposed in a substantially horizontal plane and in contact with the surface to be cleaned, the lower run of such brush traveling over a pan whereby the refuse engaged by the respective portion of the lower run of the brush will be carried upon and over such pan, the discharge end of the pan communicating with a conveyer which latter in turn has communication with an elevator whereby the refuse delivered to the conveyer is discharged into a receptacle.

It is also my purpose to provide a machine of the type set forth wherein the brush may be actuated into and out of contact with the surface to be cleaned and which will embrace few parts and these so correlated and arranged as to reduce the possibility of derangement to a minimum.

Furthermore, I aim to provide a street sweeping machine which will embrace the desired features of simplicity, efficiency and durability and one wherein the various elements of the machine will be under the complete and convenient control of the operator of the vehicle.

With the above and other objects in view, the invention consists in the construction, combination and arrangement of parts hereinafter set forth in and falling within the scope of the claim.

In the accompanying drawings; Figure 1 is a view in side elevation of a street sweeping machine constructed in accordance with my present invention. Fig. 2 is a top plan view thereof. Fig. 3 is an enlarged fragmentary side elevation showing the means for elevating and lowering the brush. Fig. 4 is a top plan view of the pan.

Referring now to the drawings in detail, 1

designates a wheeled vehicle which, in the present instance, is driven by means of a hydrocarbon engine 2 adapted to be coupled up to a driving shaft 3 arranged longitudinally of the vehicle approximately centrally thereof. The rear end of the driving shaft terminates short of the rear axle and is equipped with a bevel gear 4 meshing with a similar gear 5 keyed upon a transverse shaft 6 journaled in suitable bearings carried by the vehicle frame and arranged parallel with the rear axle. The outer ends of the transverse shaft 6 are equipped with sprocket wheels 7, 7, while fast to the rear wheels of the vehicle upon the inner sides thereof are sprocket wheels 8, 8 and over the sprocket wheels 7, and 8 are trained endless chains 9 by means of which motion is imparted to the traction wheels of the vehicle upon the coupling of the engine shaft with the driving shaft 3.

Mounted upon the frame of the vehicle is a box-like receptacle or container 10. Journaled in suitable horizontally alining bearings depending from the frame of the vehicle is a shaft 11 carrying a drum 12, while depending from the frame of the vehicle at the rear of the bearings carrying the shaft 11 are brackets 13, 13 in which are mounted 85 for sliding movement horizontally alining bearings 14 carrying a shaft 15 and upon the shaft 15 is fixed a drum 16. The drum 16 is disposed in a plane below that of the drum 12 and at the rear of the latter and both drums are preferably of a length equal to the transverse dimension of the vehicle. Over these drums is trained an endless traveling brush 17 inclined relatively to the horizontal, incident to the positions of the 95 drums, while arranged transversely of the lower run of the brush and bearing upon the same adjacent to the lower end thereof is a roller 18 mounted in lateral extensions formed on lifting levers 36 and acting upon the lower run of the brush to hold the bottom portion thereof in a substantially horizontal plane and in contact with the surface to be cleaned, as clearly illustrated in Fig. 1 of the drawings. Mounted below the lower 100 run of the brush and lying parallel with the inclined portion thereof is a pan 19 over which the brush is adapted to travel. This pan 19 is of a width equal to that of the brush and has the upper or discharge end thereof formed to provide a horizontal trough 20 within which is rotatably mounted a horizontally disposed spiral conveyer 21. The outlet end of the conveyer 21 com-

105
110

municates with an elevator 22 comprising, in the present instance, a roller 23 keyed upon the extremity of the shaft of the spiral conveyer at the discharge end thereof, a 5 roller 24 journaled in horizontally alining bearings carried by the upper ends of standards 25 uprising from the receptacle 10, and an endless belt 26 trained over the drums or rollers 23 and 24 and working through a slot 10 or opening in the bottom of the receptacle 10.

In this embodiment of my invention, the driving mechanism for the brush, conveyer and elevator comprises a countershaft 27 journaled in horizontally alining bearings 15 carried by the frame of the vehicle and arranged at right angles to the driving shaft 3 and having one end equipped with a bevel gear 28 meshing with a similar gear 29 on the shaft 3. Keyed upon the outer end of 20 the countershaft is a sprocket wheel 30, while keyed upon the adjacent ends of the shaft 11 of the brush 12 and the shaft carrying the spiral conveyer 21 and the roller 23 of the conveyer 22 are sprocket wheels 25 31, 32 and over these sprocket wheels 31 and 32 is trained an endless chain 33. Upon the outer extremity of the shaft of the roller 12 is a second sprocket wheel 34 and over the sprocket wheels 30 and 34 is 30 trained an endless chain 35.

In practice, the vehicle travels over the surface to be cleaned and the horizontal portion of the lower run of the brush 17 engages the surface of the road or street. 35 In the rotation of the driving shaft 3 motion is transmitted to the countershaft 27 and through the chain 35 and sprockets 30 and 34 to the shaft 11 of the drum 12 of the brush thereby actuating the latter. Simultaneously with the operation of the brush motion is transmitted to the shaft carrying the lower roller of the elevator 22 and the spiral conveyer 21 thereby actuating the spiral conveyer and the elevator. 40 45 As the brush continues to revolve the dirt and refuse is carried over the pan 19 and discharged from the upper end of the latter into the trough 20, while the spiral conveyer delivers such dirt and refuse to the elevator 22, the latter, in turn, discharging the refuse into the receptacle 10.

In order that the lower end of the brush 17 may be lowered and elevated so that the brush may be thrown into and out of action, the vertically slidable bearings of the shaft 15 of the lower drum 16 of the brush are connected with lifting rods 36 and connected adjacent to the upper ends thereof through the medium of a horizontal rod 37. 55 60 Loosely surrounding the rod 37 is a pulley 38 having the periphery thereof formed with a groove, while fastened to the under surface of the frame of the vehicle adjacent

to the rod 37 is a cord 39 or other flexible element trained under the pulley 38 and 65 lying within the groove thereof and having the other end thereof connected with the periphery of a disk 40 capable of rocking movement and connected with a hand lever 41. By means of this construction, it 70 will be seen that when the hand lever 41 is actuated in one direction the disk 40 will be rotated and the looped portion of the cord 39 shortened thereby moving the rods 36 and the bearings connected thereto upwardly. On the other hand, when the direction of the movement of the lever 40 is reversed the loop in the cord 39 is increased whereby the roller 16 carried by the bearings connected with the rods 36 is lowered. 80 In the present instance, a seat 42 is mounted upon the forward end of the vehicle frame in advance of the receptacle 10.

From the foregoing description taken in connection with the accompanying drawings, the construction and mode of operation of my improved street sweeping machine will be readily apparent. It will be seen that the endless brush is inclined relatively to the horizontal, while the bottom 90 portion of the lower run of the brush is held in a substantially horizontal plane so as to provide ample contact between the brush and the surface to be cleaned.

While I have herein shown and described 95 one preferred form of my invention by way of illustration, I wish it to be understood that I do not limit or confine myself to the precise details of construction herein described and delineated, as modification and variation may be made within the scope of the claim without departing from the spirit of the invention.

I claim:

A device of the class described comprising, in combination, a vehicle, a pair of brackets depending therefrom, a drum, bearings for said drum mounted for vertical adjustment in said brackets, a second drum supported by said vehicle at a higher 110 level than said first mentioned drum, a pan, a brush passing over said drums and bearing upon said pan, lifting rods secured to said bearings and having lateral extensions, a pressure roller mounted in said extensions 115 and adapted to force the brush into contact with the lower edge of the pan, and means for elevating said bearings, rods, and roller.

In testimony whereof I affix my signature in presence of two witnesses.

FRED S. SHAFFER.
